(57) **CLAIM**

The ornamental design for a light support device, as shown and described.

DESCRIPTION

FIG. 1 is a front perspective view of a new design for a light support device.

FIG. 2 is a front view of the design of FIG. 1.

FIG. 3 is a rear view of the design of FIG. 1.

FIG. 4 is a right side view of the design of FIG. 1.

FIG. 5 is a left side view of the design of FIG. 1.

FIG. 6 is a top view of the design of FIG. 1.

FIG. 7 is a bottom view of the design of FIG. 1; and,

FIG. 8 is a perspective view of the design of FIG. 1 in use. In FIG. 8, the broken lines depict a bicycle and string lights that form no part of the claimed design.
